UNITED STATES PATENT OFFICE.

EDWIN PUTNAM, OF NEWARK, NEW JERSEY, ASSIGNOR TO NOVELTY
MANUFACTURING COMPANY, OF WATERBURY, CONNECTICUT.

DESIGN FOR AN UMBRELLA TIP-CUP.

Specification forming part of Design No. **11,182**, dated May 6, 1879; application filed April 4, 1879
[Term of patent 7 years.]

To all whom it may concern:

Be it known that I, EDWIN PUTNAM, of Newark, in the county of Essex and State of New Jersey, have invented or produced a new and original Design for Tip-Cups for Umbrellas and Parasols, of which the following is a specification.

In the drawings, Figure 1 is a vertical section of the tip-cup, and Fig. 2 is an elevation of the same.

The tip-cup is of sheet metal, with a hollow convex rib, *a*, around the cylindrical portion of said cup to ornament the same. The bottom edge of the tip-cup is straight, and there are two lines of indentations above the rib *a*, as at *c c*, and there are three lines of indentations, *e e e*, below the rib. These form beaded-

work indentations that ornament the surface of the tip-cup.

The drawings is in an enlarged size to represent the parts more clearly.

I claim as my invention—

The design for an umbrella tip-cup, consisting of the convex rib *a* upon the cylindrical portion of the tip-cup, and the lines of beaded work *c* and *e*, respectively, above and below the rib *a*, substantially as described, and shown in the accompanying illustration.

Signed by me this 2d day of April, A. D. 1879.

EDWIN PUTNAM.
